UNITED STATES PATENT OFFICE

2,352,806
UNIVERSALLY ADJUSTABLE SWIVEL BASE

Nathan Rodney Schwartz, New York, N. Y.

Application April 29, 1943, Serial No. 485,084

7 Claims. (Cl. 248—346)

This invention relates to electric lamps of the incandescent or fluorescent type, and has more particular reference to improvements in adjustable electric lamps.

Modern industrial establishments, particularly those producing precision work, require electric lamps which may be so adjusted as to make it possible to cast light upon any spot, regardless of its angular relationship to the position of such lamps.

With this in view, it is the principal object of this invention to provide a swivel base on which an electric lamp may be mounted, by means of which a lamp attached to it may be rotatively adjusted.

Another feature of the present invention lies in the provision of a swivel base with means for automatically retaining a lamp attached to it in any adjusted position.

Still another advantage of this invention is to provide a swivel unit having means for limiting the rotative movement of a lamp mounted thereon, thus preventing damage to or twisting of the electric cable which would result from continued rotation in one direction.

And it is yet another aim of this invention to provide a swivel unit wherein one spring controls the rotative adjustment thereof.

A still further object of this invention lies in the provision of a universally adjustable base for an electric lamp, which is completely protected against entrance therein of oil, water and other foreign matter which would interfere with the efficient operation of the device.

Yet another aim of this invention resides in the provision of a universally adjustable swivel base which does not depend upon gravity in its operation and which therefor may be attached not only to a horizontal surface, such as a work bench, but as well to a vertical surface such as a wall, or to a surface of any angularity.

And it is still another aim of this invention to provide an adjustable swivel base which does not require the adjustment of wing nuts or set screws to achieve angular displacement, which is not affected by machine vibration, and which will not become loose as the result of such vibration.

These and other meritorious objects and advantages are achieved by the combination, construction and arrangement of few and simple parts, hereinafter described, and illustrated in the accompanying drawing, forming a material component of this disclosure, and in which:

Figure 1 is a longitudinal sectional view of a universally adjustable swivel base, constructed in accordance with the present invention.

Figure 2 is a bottom plan view thereof, parts being broken away to show the relative arrangement of the several parts.

Figure 3 is an exploded perspective view of the lower part of the housing and the rotation limiting washers, the several parts being drawn to an enlarged scale.

Figure 4 is a fragmentary sectional view of part of the base and part of the housing mounted therein, showing the means for limiting the rotative movement of the housing.

Figure 5 is a fragmentary sectional view of a modified form of the present invention.

Figure 6 is a sectional view of the modification, the section being taken on line 6—6 of Figure 5.

Figure 7 is a top plan view of the fibre washer for the spherical member, showing its elongated central opening.

Referring in greater detail to the drawing, the numeral 10 designates in general a thin-walled metallic housing, cylindrical in contour, which merges at its upper end into a rounded portion 11. At its lower end, housing 10 is turned rectangularly with respect to the cylindrical surface of the housing forming a flare 12. At the bottom near the outer rim thereof, flare 12 has two downreaching lugs 13 stamped out of its material, at diagonally opposite sides of the flare, the purpose of which will presently be described.

The swivel unit further comprises a hollow spherical member 14 having two flat sides 15 at opposite sides of each other. At its upper end, member 15 is provided with an integral nipple 16, extending upwardly beyond housing 10 and having interior threads 17 for a purpose to be presently explained. While nipple 16 is here described as being an integral part of swivel member 15, applicant may select to use a separate nipple which may be secured to the member 15 by welding or in any other desirable manner. Nipple 16 is cylindrical in cross-section and is provided near its upper edge with an opening through which may pass a set screw 18.

In order to prevent member 15 from rotating in housing 10 the housing is provided, near its rounded upper end with two flats 23, rounded at the top to conform to the contour of the rounded upper portion which, when assembled, will be in close proximity to and parallel with

the flat sides 15 of member 14. These flats may either be an integral part of housing 10 or they may be separate members, secured to the inner face of the housing by welding or in any other desirable manner.

Member 14 seats on a concavely curved washer 19 of fibre or other suitable material, said washer 19 being urged upwardly against member 14 by a coiled compression spring 20. Washer 19 has an opening 21 in its center, the opening being substantially oblong in its cross-section.

Compression spring 20 seats on a round metal washer 24 and, in order to prevent friction between the metal flare 12 and washer 24, there is inserted between these two members, a fibre ring, made of mica or other suitable material, as is indicated at 25, the width of ring 25 being equal to the distance between the edge of housing 10 and the rim of flare 12, so that it does not extend outwardly beyond said flare. While this ring has been found to be desirable, it may be omitted if applicant so desires.

Washer 24, at diametrically opposite sides, is provided with two substantially rectangular cut-outs 25-26 extending from the outer rim of said washer inwardly, the cut-outs 25-26 being slightly greater in width than the width of lugs 13 which are adapted to be engaged therein. Midway between the two cut-outs 25-26, washer 24 has a downreaching lug stamped out of its material, near the rim thereof, as is shown at 27 in the drawing. Washer 24 has a circular opening in its center, about which, on the bottom of said washer, an integral neck 31 is formed, upon which is mounted a friction preventing fibre ring washer 32 of mica or other desirable substance, having a central opening 33 therein. Washer 32 is of smaller diameter than the diameter of washer 24 so that, when the device is assembled, washer 32 will not cover cut-outs 25-26 or interfere with the function of lug 27.

A hollow base 34 cast out of iron or any other desirable material is adapted to house the several washers, tension spring and flared portion 12 of housing 10. This base is here illustrated as being circular in cross-section, but it may be made in any other desirable shape. It may for instance be rectangular or oblong. The upper portion of base 34 is constricted to form a shoulder by which the several elements just enumerated are retained, and the base then terminates in a neck portion 35.

All of the several elements are locked in operative position within base 34 by a metallic retainer washer 36 which is of a diameter slightly less than the diameter of the shoulder of base 34, so that the washer will fit snugly within the base, as is illustrated in Figure 1 of the drawing. The said shoulder portion is provided with a plurality of screw holes 37, each of which is adapted to have a screw or other fastening means entered therein, for securing the base to a support. Retainer washer 36 is provided, at its rim, with an equal number of cut-outs 38 to permit the passage of the fastening means. Washer 36 may be permanently secured to the inner side of the shoulder portion of base 34 and towards that end, washer 36 has a plurality of screw holes 39 through which may pass screws 40 or other desirable fastening means. A central opening 41 is formed in washer 36.

Base 34 is furthermore provided, at its side, with an opening 42 for a purpose to be presently

described, and at its diametrically opposite sides may be positioned a switch 43 of conventional construction, forming no part of the present disclosure.

5 The modification illustrated in Figures 5 and 6 differs from the principal embodiment in the manner in which the rotation limiting means is arranged. The spherical member here employed is identical with that employed in the device illustrated in Figure 1. This spherical member is retained in housing 50, the lower end portion of which is flared as at 51. At one point, flared portion 51 has formed integrally therewith a finger 52. If desired, finger 52 may be a separate unit, secured to the flare by welding or otherwise. Finger 52 lies in the path of a depending lug 53 formed on the inside of the shoulder portion of base 54. Lug 53 may be an integral part of the base, or it may be welded or otherwise secured to said base. To prevent friction between the flared portion 51 and the shoulder portion of base 54, a friction preventing fibre ring 56 may be inserted between these two elements, if desired. Compression spring 57, adapted to urge 20 the spherical member upwardly within the housing, rests on fibre washer 58 which fibre washer may be made of mica or any other desirable material, washer 58 in turn being retained in adjusted position by a retaining washer 59, both 30 the fibre washer and the retainer washer having a central opening therein.

The device may be preferably assembled in the following manner:

Friction preventing ring, if one is used, is placed 35 upon the upper face of flared member 12 of housing 10 by slipping it upon the housing and flare in an obvious manner. Housing 10 is then entered into base 34 from the bottom thereof until the flared portion 12 abuts the shoulder portion 40 of base 34. Spherical member 14 is thereupon entered into housing 10 from the bottom thereof, in such manner, that flat sides 15 will be parallel with flats 23. Concavely curved retainer ring 19 which, having a substantially oblong 45 opening in its center, is so placed into the housing, that the two narrow sides of the opening will come to lie below the flats 23. Then compression spring 20 is placed into housing 10, and washer 24 placed upon it in such manner, that the lugs 13 will enter cut-outs 25-26 of washer 24. Lug 27 will face downward, as will neck portion 31, upon which is now centered fibre disc 32, and finally retaining washer 36 is entered into the base and secured to it by passing fastening means 50 through holes 39 and corresponding holes in the inner side of the shoulder member of base 34. Boss 41 on washer 36 will face inwardly.

The operation of the device now becomes apparent. Inasmuch as the nipple 16 has interior threads, a lamp-bearing arm having exterior threads may be screwed into the nipple and, to prevent the remote possibility that one may be inadvertently severed from the other, set screw 18 may be provided as an aid in retaining the two parts in operative connection. Electric wires 60 extending from the lamp-bearing arm may be entered through the device, and for that purpose, each of the elements which comprise this swivel base has a central opening therein. The 65 electric wires may then be drawn out of the base 34 through eyelet 42, if that type of base is used, which is optional. The entire housing may be rotated up to substantially one complete revolution 70 in either direction. The housing may be rotated until lug 27 makes contact with boss 41, 75

and further rotation in that direction will be prevented. The housing can then be turned in the other direction, until the same position is reached. Obviously such rotative movement may stop at any desired position, and the device will be automatically retained in that position.

The modified form of this invention is assembled in a similar manner except that washer 24 is here eliminated, the spring resting on the fibre washer. Limitation of the rotative movement of the housing in this instance results when lugs 53 and 52 meet. Since they are in the path of one another, further rotation in the direction in which rotation was had is stopped. Rotation in the other direction is possible, until the meeting of these two members again takes place.

Many modifications of this device are possible and may be called for to suit varying requirements. One of these modifications may have to do with means for preventing the spherical member from rotating in the housing. Applicant hereabove has illustrated two flats 23 secured to the housing by welding or otherwise. These flats however may be made integral with the housing. Other means to accomplish the same end may be devised. For instance, instead of providing the housing with flats, two upreaching extensions may be secured to fibre washer 19, or made an integral part thereof. When assembled, these extensions will lie parallel with the flat side of the swivel member.

The number and relative positions of the several cut-outs may be changed, and the eyelet at base 34 may be eliminated.

Provision may be made to prevent fibre washer 19 from rotating in the housing. For instance, washer 19 may be provided with a vertical slot, adapted to engage a corresponding key in the base. The several washers below the spring, identified by the numerals 24, 32 and 36 in the principal embodiment, and by the numerals 51 and 59 in the modification, may be joined at their center opening circumferentially by a grommet, which serves the additional purpose of grounding the device.

Also, while throughout the description, reference has been made to industrial lamps, applicant in no wise desires to be restricted to the application of his invention to such purpose. The swivel base here described can be used equally effectively for many other purposes, such as desk lamps, draftsmen's lamps, home lamps and in fact, effective use can be made wherever it is desirable to vary the angularity of light rays.

There has thus been described and illustrated a simple, yet extremely efficient swivel base in two of its preferred forms. This disclosure however is to be regarded as descriptive and illustrative only, and not as limitative or restrictive to the exact details shown, and applicant reserves the right to make such changes therein, as come within the scope of the appended claims without departure from the spirit of this invention.

Having thus described the invention, what is claimed as new and desired to secure by Letters Patent, is:

1. A universally adjustable swivel base comprising a base member, a housing rotatably mounted therein, a spherical member in said housing, means in said housing urging said swivel member upwardly, a washer on which said urging means is seated, means enterable in said base member locking said housing in said base member, and means cooperating between said

washer and said locking means limiting the rotative movement of said housing.

2. In a universally adjustable swivel base member, the combination of a base, a thin-walled housing rotatably mounted therein, a spherical member in said housing, means in said housing urging said spherical member upwardly, a washer on which said urging means seats, means cooperating between said washer and said housing to engage said washer and said housing, a fibre ring interposable between said housing and said washer, a retainer washer locking said housing in said base member, and means cooperating between said first named washer and said retainer washer limiting the rotative movement of said housing.

3. A universally adjustable swivel base to which an electric lamp bearing arm may be attached, said swivel base comprising a base member having a horizontal upper surface and cylindrical sides, a central circular opening in said upper surface, a thin-walled metallic housing rotatably mounted in said opening, said housing having a cylindrical surface merging at one end

25 into a rounded apex of spherical nature, a spherical member in said housing, means integral with said housing preventing the rotation of said spherical member, a nipple integral with said spherical member, said nipple extending upwardly beyond said housing, said nipple having internal means to receive an electric lamp bearing arm, a washer on which said spherical member seats, means urging said washer upwardly against said spherical member, a washer on

35 which said urging means seats, a retainer washer locking said housing in said base member, and means cooperating between said last two washers limiting the rotative movement of said housing in said base.

40 4. In a universally adjustable swivel base to which an electric lamp arm having electric wires extending therefrom may be attached, a base member having cylindrical sides and a horizontal upper surface, a central circular opening in said upper surface, a shoulder formed in said base

45 member near the upper surface thereof, a thin-walled housing rotatably mounted in said base member, said housing having a cylindrical outer surface and merging at one end into a rounded upper portion of spherical nature, the other end of said housing turned outwardly to form a flared portion, a spherical member completely enclosed in said housing, said spherical member having two opposed substantially flat sides, a hollow cylindrical nipple integral with said spherical member at the upper end thereof,

55 means in said nipple adapted to retain an electric lamp arm, said nipple extending upwardly beyond said housing, means cooperating between said flat sides of said spherical member and said housing preventing said spherical member from rotating in said housing, a concavely curved washer on which said spherical member seats, a spring urging said spherical member upwardly, a washer for said spring, a plurality of cut-outs in said washer, downreaching means on said flared portion of said housing engaging said cut-outs, a retainer washer locking said housing in said base member, means cooperating between said two washers limiting the rotative movement of said housing, and a passageway extending downwardly through said swivel base for the passage of electric wires therethrough.

60 5. In a universally adjustable swivel base to which an electric light arm having electric wires

extending therefrom may be attached, the combination of a hollow base member having a cylindrical outer surface and a flat top, said top constricted at its center forming a neck portion, a circular opening in its center, a swivel unit rotatably mounted therein, said swivel unit comprising a thin-walled metallic housing having a cylindrical outer surface, said outer surface merging at one end into a rounded upper portion of spherical nature, the other end of said housing turned outwardly to form a flared portion, a spring-pressed spherical member completely enclosed in said housing, a nipple integral with said spherical member extending upwardly beyond said housing, said nipple having threads in its interior for attachment to an electric lamp arm, a metallic washer for said spring, a retainer washer locking said swivel unit in said base member, means cooperating between said metallic washer and said retainer washer limiting the rotative movement of said housing to slightly less than one complete revolution in either direction, and vertically extending means through said swivel unit for the passage of electric wires therethrough.

6. In a universally adjustable swivel base, the combination of a base member having a hollow interior, cylindrical sides and a flat top, said top constricted to form a neck portion, a circular opening in its center, and a swivel unit rotatably mounted therein, said swivel unit comprising a thin-walled metallic housing having a cylindrical outer surface merging at its upper end into a rounded upper portion of spherical nature, a circular opening at the top of said rounded upper portion, a spherical member completely enclosed in said housing, said spherical member having a vertical opening extending therethrough, a hollow cylindrical nipple at the top of said spherical member extending upwardly beyond said housing, threads in said nipple for attachment of an electric lamp arm thereto having electric wires therefrom, a fibre washer for said spherical member, said fibre washer having a substantially flat bottom and a concavely curved upper face, an oblong opening extending vertically through

said fibre washer, a coiled compression spring urging said fibre washer upwardly, the lower end of said housing forming a flared portion, a friction-preventing band interposable between said flared portion and said base member, a plurality of depending lugs on the under side of said flared portion a circular metallic washer for said spring, a circular opening in its center, said metallic washer provided with a plurality of cut-outs for 10 said lugs, a downreaching lug on said metallic washer, a metallic retainer washer, a plurality of screw openings therein, a boss on the upper face of said retainer washer, a circular opening in the center of said washer, said circular openings in said swivel unit for the passage of electric wires therethrough.

7. In a universally adjustable swivel base to which an electric lamp having electric wires extending therefrom may be attached, a hollow base having a flat top, said flat top constricted to 20 form a raised neck portion, a circular opening in said neck portion, a metallic housing having a cylindrical outer surface and merging at its top into a rounded upper portion of spherical nature, 25 a spherical swivel member in said housing, said swivel member having a vertical opening through its center and two substantially flat sides, said housing having means cooperating with said flat sides to prevent said swivel member from rotating in said housing, a fibre washer for said swivel member, a spring urging said fibre washer upwardly against said swivel member, a fibre washer on which said spring seats, a central circular opening therein, a retainer washer to lock said 30 housing in said base, means cooperating between said base and said retainer washer to limit the rotative movement of said housing to slightly less than one complete revolution in either direction, 35 a plurality of slots in said housing at opposite sides thereof, extending from said rounded upper portion to points therebelow to receive said nipple for angular adjustment of said swivel member up to 90 degrees relative to its normal axis, said central circular openings forming a passageway for the passage of electric wires therethrough.

NATHAN RODNEY SCHWARTZ.
